COMBINATION HEATER AND MUFFLER CONSTRUCTION

Application filed December 27, 1926. Serial No. 157,192.

This invention relates to a combination heater and muffler.

The chief object of this invention is to provide a muffler of such construction that in addition to serving its normal purpose of muffling the explosive sounds of an internal combustion engine, said muffler is adapted to heat air passing thereover and under confinement, said heated air thereupon being suitable for vehicle compartment heating.

Another object of the invention is to construct the combination heater and muffler such that during such seasons of the year when heating is not desired the heater will be self ventilating.

One feature of the combination heating muffler consists in the specific construction of the combination heating muffler, and another feature consists in the specific construction of the ventile air heating casing and the third feature of the invention consists in the association of the two such that a return bend passage is obtained.

Another feature of the invention consists in the arrangement of the device such that it may be readily supported upon a motor vehicle and the heating muffler readily substituted for the standard muffler provided.

The full nature of the invention will be understood from the accompanying drawings and the following description and claims:

In the drawings Fig. 1 is a side elevational view of a portion of the motor vehicle showing the internal combustion engine and heating system. Fig. 2 is an enlarged longitudinal sectional view through the heating system, the exhaust including the muffler being shown in elevation. Fig. 3 is a top plan view of the exhaust heating muffler with a portion shown in quarter section. Fig. 4 is a transverse sectional view taken on lines 4-4 of Figs. 2 and 3.

In the drawings 10 indicates an internal combustion engine having an exhaust 11. The motor vehicle includes the dash 12, toe-board 13 and floor board 14, as well as the step supporting bracket 15. All of the foregoing is of the usual construction.

The details of the combination heating muffler are shown in all of the figures and

the same includes a casing 16 having an inlet end 17 and a discharge end 18. An exhaust pipe 19 is slidably receivable by inlet 17 and has a threaded connection as at 20 in the usual manner with the exhaust manifold 11, 55 and said pipe 19 is secured in adjusted position through the instrumentality of the locking screw bolt 21. Exhaust pipe 22 is receivable by the outlet 18 of the muffler and is rigidly secured thereto by suitable means such as the set screw or rivet 23.

The muffler is constructed such that it is not only adapted to serve as a muffler and thereby replace the standard muffler construction provided, but it serves as an air heater as well. The body portion 16 includes the central chamber 24 which extends from the inlet 17 to the outlet 18, but direct passage therethrough is prevented by the inwardly extending baffles 25 terminating short 70 of the middle of the passage and outwardly extending interposed baffles 26 extending towards the sides from the center, all of said baffles being connected at the tops and bottoms to the top and bottom portion of the casing. 75 The casing upon its upper and lower exterior surface is shown provided with parallel ribs or heat radiating surfaces 27 and upon its lateral faces is provided with flat flanges or surfaces 28, the same being laterally apertured at the ends as at 29 for heater casing anchorage. The heater casing consists of U or channel-shaped sheet metal members 30 and 31, the same having overlapping parallel portions positionable adjacent the flanges 28 and secured in muffler enveloping formation, see Fig. 4, by suitable means such as the screws 31 receivable by the threaded openings 29. The continuation of the flanges from end to end insures a partition arrangement forming an upper and lower chamber or passage in the heater casing. The upper channel member has an angular extending portion 33 including an aperture 33a that receives the outlet 18 of the muffler. The screw bolts 32 at this end of the heater rigidly clamp a U-shaped strap closure 34 in closed position, see Figs. 1 and 2, to form a return bend passage through the heater casing.

The upper channel member has an angular extending portion 33 including an aperture 33a that receives the outlet 18 of the muffler. The screw bolts 32 at this end of the heater rigidly clamp a U-shaped strap closure 34 in closed position, see Figs. 1 and 2, to form a return bend passage through the heater casing. After loosening bolts 32 and tilting the 100

U-shaped strap counterclockwise until it lies parallel to the lower portion 30 it is secured in abuttable relation thereto permitted by the elongated slot 35 in the member 34 venting the air passage.

The strap 36 through the instrumentality of the clamping bolt 37 and the anchoring bolt 38 supports the lower end of the muffler and also the heater through the step bracket 10 15 standard on the vehicle.

An air intake 39 discharges into the lowermost channel formed by the lower member 30 of the heater casing and the lower part of the muffler. Air partially heated by passing 15 over the engine and through the radiator passes through the flared intake 39 and is discharged into the lower passage in the heater casing. It passes through the lower passage, engages the deflecting ventilator 20 valve 34 and the angular portion 33 and returns along the upper channel formed between the upper heater casing member 31 and the top of the muffler. The upper member 31 at its upper end includes a rectangular 25 outlet 40 extending laterally of the body portion. The open end of the upper end of the member 31 is closed by a deflecting valve 41 pivotally supported at 42, and this valve when in the position shown in Fig. 2, serves 30 as a closure for the channel and insures discharge of the heated air through the outlet 40 and prevents its discharge through the open upper end of the heater. When the valve member 41 is tilted clockwise, this substantially 35 closes the outlet 40 and opens the open end of the heater. The bolts 42 are adapted to clampingly secure, as well as pivotally support for said adjustment, the valve member 41. Thus, when the deflecting valve 40 40 and the deflecting valve 41 are positioned in open relation, to wit, that oppositely from conditions shown in Fig. 2, free ventilation will be obtained through the heater casing and no heated air will be discharged through 45 the outlet 40 and thus venting the heater. When the deflecting valves are positioned as 50 shown in Fig. 2 the heated air is caused to pass over the muffler surfaces, become heated and thereupon be discharged through a register construction 43 suitably mounted in the toe-board 13 and have a telescopic connection with the outlet 40. This telescopic connection permits of adjustment for each individual vehicle. A plurality of heat radiating fins 27 are provided to insure the 55 rapid transfer of heat from the muffler to the air passing thereover, and not only serve to direct the flow of the air longitudinally of the muffler and the heater casing, but also 60 prevent to a considerable extent local circulation in the heater.

The invention claimed is:

1. A combination heating muffler comprising a muffling member for the exhaust of an engine, a casing peripherally enveloping said

muffler, lateral walls projecting outwardly from the muffler and dividing the casing into a pair of channels in the casing with the included muffler as a partition, an air intake to one channel at one end of the casing, a combination deflecting valve at the opposite end of the casing and adapted to close the same, a hot air discharge adjacent the air intake and in the other channel formed by the muffler within the casing, and a valve means adjacent thereto for venting the passage between the first-mentioned valve and the discharge and for controlling said discharge.

2. A combination heating muffler, comprising a muffling member for the exhaust of an engine, an air heating casing peripherally enveloping the muffling member, said casing at one end including an air intake and an air discharge, lateral walls projecting outwardly from the muffling member to the casing, said walls and member constituting a partition for forming a pair of channels in the casing, one channel communicating with the discharge and the adjacent end of the other channel communicating with the intake, the opposite ends of said channels communicating with each other, and a combination deflecting valve positioned adjacent the last-mentioned channel communication for venting the same.

In witness whereof, we have hereunto affixed our signatures.
